INVENTOR

ROBERT AERNOUT BARON VAN LYNDEN

BY

John Lotka

ATTORNEY

UNITED STATES PATENT OFFICE.

ROBERT AERNOUT BARON VAN LYNDEN, OF Utrecht, NETHERLANDS, ASSIGNOR, BY MESNE ASSIGNMENTS, TO AMERICAN THERMOPHONE COMPANY, OF BOSTON, MASSACHUSETTS, A CORPORATION OF MASSACHUSETTS.

THERMIC TELEPHONE.

1,389,230.

Specification of Letters Patent. Patented Aug. 30, 1921.

Application filed October 12, 1917. Serial No. 196,254.

To all whom it may concern:

Be it known that I, ROBERT AERNOUT BARON VAN LYNDEN, a subject of the Queen of the Netherlands, and residing at Utrecht, 5 in the Netherlands, have invented certain new and useful Improvements in Thermic Telephones, (for which I have filed applications in Germany, December 23, 1916; Holland, September 15, 1916; and Norway, July 10 9, 1917,) of which the following is a specification.

My invention relates to improvements in thermic telephones and has for its object to provide means, whereby the mechanical 15 manufacture of the heating-conductors of said thermic telephones is greatly facilitated.

According to my invention, I form the heating-conductors, by a helical coil of Wollaston wire or the like, the windings of 20 which correspond to half the number of heating-conductor arcs connected in parallel. This coil preferably is flattened and with its central flattened portion inserted between two contact pins to which its windings are 25 soldered or otherwise fastened. In this manner, the bent portions of the windings project on either side of said pins so as to form a number of arc-shaped heating-conductors which are connected in parallel.

30 This heating-conductor device is, where Wollaston wires are used, immersed into an acid bath first with the wire arcs projecting on one side of the pins and then with those projecting on the other side, so that all the 35 heat conductor arcs, whatever their number, may be etched to the desired length of sound emitters by only two manipulations.

If the two contact pins are fixed in an 40 insulating block at one end, a very simple and solid construction for thermic telephones may be provided by inclosing the unit consisting of the insulating block, the contact pins and the heating-conductor arcs connected therewith, in a casing having a 45 cover which is perforated to receive the free ends of said pins. Contact sleeves may be arranged over the free ends of said pins so as to be brought in engagement readily with a two pin plug to make connection with 50 a cord or the like.

Reference is to be had to the accompanying drawings in which I have illustrated a preferred form of my improved arrangement in thermic telephones.

Figure 1 is a plan view and Fig. 1^a an elevation of the contact pins fixed in an insulating block, Fig. 2 is a side view of the heating-conductor device showing the wire coil in position on the contact pins, Fig. 3 is a plan view of the parts shown in Fig. 2, 60 Fig. 4 is a sectional view of the heating-conductor device embedded in a casing and Fig. 5 is an elevation, partly in section, of the complete thermic telephone with connections. 65

The contact pins 1 are fixed at one end in an insulating block 2 and provided with collars 3 near their free ends. A wire coil 4, see Figs. 2 and 4, is arranged between pins 1 and attached to them in any suitable manner, for instance by soldering. This coil which is originally circular, as shown in Fig. 3 by dotted lines, is flattened, as illustrated in Fig. 3. The straight dotted lines 5 in this figure indicate the level up to which the 75 arc-shaped portions of the heating-conductor coil are exposed to the etching action of the acid bath.

The unit formed by the contact pins 1, the insulating block 2 and the heating-conductors 4 is inserted in a cylindrical casing 6, see Fig. 4, which has a cover 7 made of insulating material. The free ends of pins 1 pass through perforations of cover 7 which 80 abut against their collars 3. The perforations are widened at their lower ends to receive contact sleeves 8 (shown detached in Fig. 4) into which the pins 1 project and in which contact pins such as 9 may be inserted. The upper end of cylinder 6 which 85 is flush with the surface of insulating block 2, is closed by a perforated cap 10.

The entire thermic telephone is inclosed in a sleeve 12, as shown in Fig. 5, which is threaded at one end and engages a contact 95 plug 11 also threaded and provided with contact pins 9, connected with a cord or other wire conductor attached to the said plug.

I claim:

1. In thermic telephones, a pair of parallel contact pieces, a support for holding said contact pieces in position, and a wire coil located between said contact pieces, with the axis of the coil parallel to said contact pieces, and each turn of the coil conductively attached to said contact pieces. 105

2. In thermic telephones, an insulating

support, contact pieces secured thereto, and a wire coil located between said contact pieces and having its several turns secured to said contact pieces at opposite sides of the 5 coil.

3. In thermic telephones, the combination of a pair of contact pins fixed to an insulating block, a wire coil inserted between and conductively connected with said contact 10 pins, and a casing inclosing the unit formed by said contact pins, said insulating block and said wire coil, said casing being provided with a cover made of insulating material and having openings adapted to receive the free ends of said contact pins.

4. In thermic telephones, a wire coil, contact pieces located at opposite sides of said coil and extending lengthwise thereof, and secured conductively to the several turns of 20 the coil on the outer surface of the coil, and a support for said contact pieces.

5. In thermic telephones, contact pins provided with collars adjacent to one end, a support connecting said pins at the other 25 ends, and a wire coil located between said support and said collars, in contact with said pins at its several turns.

6. In thermic telephones, a wire coil of oval cross section, contact pieces located at 30 opposite sides of said coil and extending lengthwise thereof, and secured to the several turns of the coil, and a support for said contact pieces.

7. In thermic telephones, a wire coil, contact pieces located at opposite sides of said coil, lengthwise thereof, and connected with 35

the several turns of the coil, and a casing for containing said contact pieces and wire coil, said casing having openings to receive the ends of said contact pieces. 40

8. In thermic telephones, a wire coil, and conducting contact pieces extending lengthwise of said coil and engaging all the turns thereof at the same time.

9. In thermic telephones, a wire coil, and 45 conducting contact pieces, insulated from one another but in engagement at all times with all the turns of said coil.

10. In thermic telephones, a wire coil, conducting contact pieces insulated from each 50 other and extending lengthwise at opposite sides of said coil, and in engagement with the several turns of said coil, and a support for said contact pieces.

11. In thermic telephones, a wire coil comprising alternate sections of etched and unetched Wollaston wire, and contact pieces, insulated from each other and in engagement with unetched portions of said wire coil, at 55 each turn thereof. 60

12. In thermic telephones, a wire coil, and conducting contact pieces insulated from one another and engaging the several turns of said coil on its outer surface.

In testimony whereof, I have signed this 65 specification in the presence of two subscribing witnesses.

ROBERT AERNOUT BARON van LYNDEN.
